G. H. & W. P. Woolley, of Hartford, Conn.
Letters Patent No. 2071-Dated May 16, 1865.
Design for a Coffin.

DES. 2071

The schedule referred to in these letters Patent and making part of the same.

To all whom it may concern:

Be it known that we, G. H. and W. P. Woolley,
of the City and County of Hartford and State of Connecticut, have
invented certain new and original designs for Burial Caskets,
and we do hereby declare that the same is described and repre-
sented in the specification and photographic views, reference
being had to the letters marked thereon which indicate
like parts.

In the accompanying views A is the side of the casket.
B the end, configurated with ornamental mouldings. It is a flat-
tened corner. D is a curved side proper. E is a raised panel
surrounded with a plain or gee moulding. F is configurated
with ornamental mouldings H.

What we claim, therefore, and desire to secure by Let-
ters Patent is: The design for a Burial Casket substantially as herein
illustrated and described.
